LOADING MACHINE

Edward G. Lewis, London, Ohio, assignor to The Jeffrey Manufacturing Company, a corporation of Ohio

Application August 1, 1941, Serial No. 405,068

30 Claims. (Cl. 192—21)

This invention relates to loading machines particularly adapted for loading coal in a coal mine, and one of its objects is the provision of improved power-transmission mechanism for operating traveling conveyor means embodied in the machine.

Another object of the invention is the provision of clutch controlled reversible power-transmission mechanism for propelling means of the loading machine.

A further object of the invention is to provide a novel controlling means for a plurality of friction clutches, particularly useful in connection with loading machines.

More particularly it is the object of the present invention to provide friction clutch controlled reversible power-transmission means for loading machine propelling means and cable reel mechanism so that as the machine moves forward, the cable reel may be paid out and as the machine moves rearwardly, the cable reel may be wound up.

Other objects of the invention will appear hereinafter, the novel features and combinations being set forth in the appended claims.

In the accompanying drawings,

Fig. 1 is a vertical longitudinal sectional view of the loader comprising my invention showing particularly the rear end portion thereof;

Fig. 2 represents a sectional plan view of the power-transmission mechanism for the gathering conveyor and power-transmission mechanism for the cable reel together with the truck propelling mechanism;

Figs. 3 and 3a, placed end to end, are side elevations of the entire track-mounted loading machine embodying my improvements;

Fig. 4 is a transverse sectional view taken on the line 4—4 of Fig. 1 looking in the direction of the arrows;

Fig. 5 is an enlarged detail view showing the operating mechanism for applying the main or starting clutch;

Fig. 6 is an enlarged sectional view taken on the line 6—6 of Fig. 4, looking in the direction of the arrows;

Fig. 7 is an enlarged sectional view taken on the line 7—7 of Fig. 4, looking in the direction of the arrows;

Fig. 8 is an elevational view of the manual mechanism for operating the friction clutches;

Fig. 9 is a sectional plan view taken on the line 9—9 of Fig. 8;

Fig. 10 is a sectional elevation taken on the line 55

10—10 of Fig. 8 looking in the direction of the arrows;

Figs. 11, 12 and 13 are enlarged detail views of the lost-motion connections between the lever of Figs. 8 and 10 and the friction clutches shown in Fig. 4, Fig. 12 being a section taken on the line 12—12 of Fig. 11 looking in the direction of the arrows, and Fig. 13 being a section taken on the line 13—13 of Fig. 11 looking in the direction of the arrows; and

Fig. 14 is another detail view.

The loading machine illustrated in the accompanying drawings comprises a track mounted truck 40 upon which is mounted a gathering conveyor 41 and a discharge conveyor 42, the former being adapted to dig into and gather loose or semi-compact coal and convey it to the latter by which it is discharged into track mounted coal cars.

20 As will be hereinafter described in complete detail, power means is provided to propel the loading machine along a mine track at a relatively fast speed and to operate it along such mine track at a feeding or operating speed while at 25 the same time operating the gathering and discharge conveyors to gather and load coal into coal cars.

The truck 40 comprises a main frame formed by longitudinally extending side members 44 rigidly attached together at their forward ends by an arcuate cross-piece preferably welded to the side members 44 and rigidly attached at their rear ends, as by welding, to an arcuate cross-piece 46 (Fig. 2) having removably attached thereto an arcuate bumper plate 47 held in place by nuts and bolts 48.

Adjacent its forward end the main frame comprises a bed plate 49 (Fig. 2) rigidly attached to the tops of the side members 44 and front cross-piece as by welding. The gathering conveyor 41 and the drive means therefor are supported on this bed plate 49.

45 Adjacent its rear end, the main frame is provided with a bed plate 50 (Fig. 2) which is rigidly attached to the bottoms of the side members 44 and the rear cross-piece 46. The bed plate 50 supports the single drive electric motor 224 which drives all of the apparatus on the loading machine and supports most of the power-transmission 50 gearings for controlling the loading machine.

The truck 40 is mounted upon a pair of forward track engaging flanged wheels 51. The truck 40 is also provided with rear track engaging flanged wheels 56, 56 mounted upon axle 57 journaled in bearing boxes 58, 58 (Fig. 2) slidable longitudi-

nally in guideways. Gearing mechanism 61 readily accessible from the sides of the truck 40, is provided for adjusting the bearing boxes 58, 58 longitudinally in unison along the guideways.

The axles are provided with sprockets respectively which are connected together by an endless chain 65 to assure their movement in unison. Axle 57 also carries a drive sprocket 59 by which it is driven, as hereinafter described in full detail. It is thus evident that driving power will be supplied to all the track engaging wheels.

It will be evident that the thrusts received by the gathering conveyor 41 will be transmitted to the truck 40 through the casting 73 and therefore this casting and the journal bearing 70 associated therewith are made of very rugged construction.

The bottom plate 69 is removably attached to the casting 73 by a threaded ring 76 threaded to the top of the said casting 73 and held locked by a set screw.

The discharge conveyor 42 comprises three articulated parts including a stationary hopper 155 supported upon the front bed plate 49 of the truck 40 by spaced side brackets. This hopper 155 comprises spaced side members 158 and a downwardly inclined rear chute formed integral with said side plates 158. The chute is adapted to receive the material, such as coal, as it discharges from the rear end of the gathering conveyor 41.

Pivottally attached to the hopper 155 by means of spaced side brackets 166, 166 (Fig. 1) carried by the side members 167, 167 and journaled on pins 168, 168, is a discharge boom 169. It is evident that the boom 169 is pivoted about a horizontal axis formed by pins 168 for vertical swinging movement with respect to the hopper 155 and the truck 40. The discharge boom 169 is formed in two parts comprising the forward part 170 and the rear part 171 which are pivotally attached about a vertical axis, the rearward part 171 being swingable horizontally about such vertical axis. The forward part 170 of the boom 169 comprises a bottom plate 172 which acts somewhat as a continuation of the bottom plate 162 of the hopper 155.

A guide sprocket for the chain 165 is provided at the rearmost end of the rear part 171. At the forward end of the discharge conveyor 42 I provide within the hopper 155 a centrally disposed guide sprocket for the chain 165. To effect the driving of the chain 165 I provide a drive sprocket 189 (Fig. 1). To maintain the chain 165 in meshing relation with the drive sprocket 189 I provide a curved wear shoe 192 mounted on the false bottom plate 164.

The chain 165 carries a plurality of spaced flights which, during the upper run of the chain 165, are adapted to scrape over the false bottom plates 164, 173 and 180 successively, thereby conveying material rearwardly from the hopper 155 for discharge into the mine cars.

The rear end of the discharge conveyor section 170 is supported by the hydraulic motor 194 for adjustment in elevation on the pivot 168.

Attention is now directed to the power transmission mechanism connected to the various devices to operate the same. At the outset it may be stated that only a single or common electric motor 224 is relied upon as the primary source of power to effect a driving of all the devices of a loading machine. This electric motor 224 is mounted upon the rear bed plate 50 of the truck 40 and compactly positioned below the discharge conveyor 42 which extends upwardly and rear-

wardly from the hopper 155. Due to this positioning of the electric motor 224 it is possible to provide a very large and powerful motor which is capable of effecting any and all of the drives required at any time while maintaining a machine of low height to permit its use in a relatively low roof mine or low vein coal mine.

The electric motor 224 is provided with a forwardly extending armature shaft 225 (Fig. 1) carrying a beveled drive pinion 226 meshing with a beveled ring gear 227 which is rigidly attached to the housing 228 of a friction clutch 229. The housing 228 is keyed to a vertical shaft 230 which is mounted at its top in a bracket 231 rigidly attached to the main frame of the truck 40. An anti-friction ball bearing 232 is interposed between the bracket 231 and the shaft 230, which is held in place by a removable cap 233.

The bottom of the shaft 230 is supported in a bracket 234 (Fig. 4) formed rigid with the bottom plate 50, said support being through an anti-friction ball bearing 235. Keyed to the lower end of the shaft 230 and above the ball bearing 235, is a bevel gear 236. It should be noted that the gear 227 and the gear 236 are both keyed to the shaft 230, and both will therefore be driven together at all times from the motor 224.

Journaled loosely on the central portion of the shaft 230 is a clutch member 237. Splined on the interior of the housing 228 and on the exterior of the clutch member 237, which members 228 and 237 comprise co-operating clutch members, is a plurality of overlapping stacked friction plates 238, alternate ones of which are connected to the housing 228 and the clutch member 237, respectively. Adjacent its bottom the clutch member 237 is provided with an integral extended flange 239 to which is secured a gear 240. The flange 239, in addition to supporting the gear 240, also acts as one compression member for the friction clutch plates 238.

To effect the compression of the clutch plates 238 (Fig. 4) and thus to effect engagement of the clutch members 228 and 237, I provide a compression ring 241 within the housing 228. The circular flange of the ring 241 bears against the plates 238. Downward movement of the ring 241 to effect the aforementioned compression action is effected by a plurality of pins 242 which extend through apertures in the housing 228 and are carried by a ring 243 operable through an anti-friction ball bearing 244 operable by a trunnion collar 245 which is controlled by a shipper 246 keyed on a shaft 247 (Fig. 1), which shaft 247 is journaled at one end in an upwardly extending plate 248 (Fig. 4) rigidly attached to a false bottom plate 249 which, in turn, is rigidly attached to the main frame of the truck 40.

Adjacent its other end the shaft 247 is supported in a pair of downwardly extending apertured plates 250, 250 (Fig. 2) which are bolted to the brackets 231.

Rocking movement of the shaft 247 to urge the collar 245 (Fig. 4) downward, will cause an application of the friction clutch 229 to drive the gear 240. When the shaft 247 is released the clutch 229 will automatically become disengaged due to lack of sufficient clamping pressure on the plates 238. The operating means for rotating the shaft 247 is shown in Figs. 4 and 5.

The gear 240 which is controlled by the clutch 229 is individual to a gear train for driving the gathering conveyor chains. The gear 240 meshes with the idler gear 251 mounted upon an anti-friction supported shaft 252 journaled in a cup

253 (Fig. 1) and removably attached to the front bed plate 49. The gear 251 in turn meshes with the large gear 254 carried by a shaft 255 on anti-friction bearings in the previously described casting 73. It should be particularly noted that since the vertical axis about which the gathering conveyor 41 swings is along the axis of the shaft 255, power can be transmitted to said gathering conveyor through the gear 254 while the gathering conveyor is in any desired position of angular adjustment relative to the truck frame 40 or relative to the mine track comprising the rails 66.

The large gear 254 meshes with one of a pair of intermeshing large gears which are journaled in the forward bottom plate and the top plate of the turntable and which drive the sprockets through vertical shafts. The two drive sprockets are driven in reverse directions and at the same speeds, thereby driving the gathering chains at the same speeds but in reverse directions, with the flights on one chain in fixed relation to the flights on the other chain.

Attention is now directed to the gear train which is operative to drive the truck 40 either forwardly or reversely and at either a fast tramping or transportation speed or at a low feeding or sumping speed. This gear train or power transmission mechanism for the truck propelling means, includes the previously described gear 236 which is driven directly from the motor 224. The gear 236 is beveled and meshes on opposite sides with bevel gears 258, 258 of reversing friction clutches 259 and 260, respectively, as shown in Fig. 4.

Except in respects hereinafter described in full detail, the clutches 259 and 260 are similar and therefore a detailed description of clutch 259 will suffice for both. The clutch 259 comprises a housing 261 to which the bevel gear 258 is keyed. The housing 261 is loosely journaled on a longitudinally extending hollow drive shaft 262 to which is keyed a clutch member 263. Housing 261 and clutch member 263 carry alternate stacked friction clutch plates 264 which may be compressed into clutch engaging position by an operating ring 265 adapted to be engaged by the opposed heads of an operating key 266 (Fig. 7) which extends through an elongated slot 267 in the drive shaft 262 and through an elongated slot 268 (Fig. 6) in an operating shaft 269 and is removably held in place by said end heads, one of which is formed by spaced bars 265' rigidly and removably attached by rivets 266'.

By referring to Fig. 4 it will be seen that the bevel gears 258 are rotated by the bevel gear 236 in reverse directions. Consequently, when the clutch 259 is applied, the shaft 262 will be rotated in one direction by the motor 224, and when the clutch 260 is applied, the shaft 262 will be rotated in the reverse direction.

Elongated slots 268 are so spaced with respect to the operating shaft 269 that both of said clutches 259, 260 may be in disengaged or released position at the same time, and when the shaft 269 is shifted to the right, as viewed in Fig. 4, the clutch 260 will be applied and when shifted to the left the clutch 259 will be applied.

The opposite ends of the shaft 262 are mounted in appropriate journal bearings 270 and 271 both formed rigid with the false bottom plate 249.

Keyed to the shaft 262 is a drive pinion 272 as shown in Fig. 4. By referring to Fig. 2 it will be seen that the pinion 272 drives a variable speed reduction mechanism comprising a gear 272 constantly in mesh with the gear 272. The gear 273

is keyed to a pinion 274. Both the gear 273 and the gear 274 are journaled loosely on the countershaft 275 mounted for free rotation in journals which are carried by the false bottom plate 249. The pinion 274 meshes with a larger gear 278 keyed to a pinion 279. The gear 278 and pinion 279 are mounted upon a shaft 280 journaled in bearings 281, 281. The pinion 279 meshes with a gear 282 which is loosely journaled on the counter-shaft 275.

The gears 273 and 282 are provided with clutch jaws 283 and 284 respectively which cooperate with clutch elements 285, 286 respectively having appropriate co-operating jaws. A shipper 287 is provided for the clutch elements 285 and 286. This shipper is adjustably mounted on a shiftable shaft 288 slidably at one end in a journal 289 (Fig. 2) carried by the side plate 44. The shaft 288 at its other end is pivoted to an operating lever 290 mounted on the bracket 291 carried on the plate 248, as shown in Figs. 4 and 5.

As clearly illustrated in Fig. 5, the lever 290 is provided with locking mechanism 292 cooperating with a plate 294 having three holes 295 (Fig. 4) means of which the shaft 288 may be locked in any one of three positions.

In the position illustrated in Fig. 4, both of the clutch elements 285 and 286 of Fig. 2 are in clutch releasing or disengaging position and therefore no drive whatever will be transmitted to the countershaft 275. If the shaft 288 is moved to the left, as viewed in Fig. 4, clutch element 285 will be moved to applied or engaged position which will effect a high speed connection between the drive shaft 262 and the countershaft 275. When the clutch element 286 is moved into applied or engaged position by moving the shaft 288 to the right, as viewed in Fig. 4, a low speed connection will be effected between the drive shaft 262 and the countershaft 275. For a given direction of rotation of the shaft 262 the shaft 275 will be rotated in the opposite direction whether the high speed or low speed gearing is in operation. This can readily be understood by referring to Fig. 2 from which it will be seen that if the gear 272 rotates in a clockwise direction, the gear 273 will be rotated anti-clockwise and also the shaft 275, whether the clutch 283, 285 is applied or whether the clutch 284, 286 is applied. Reversal of rotation of the shaft 275 either at high transportation speed or low feeding speed is effected by means of the reversing mechanism shown in Fig. 4 and described more fully hereinafter.

Keyed to the countershaft 275 is a drive sprocket 293 (Fig. 2) which drives the sprocket 59 through a drive chain 293'. The drive sprocket 59 is connected to the axle 57 and the wheels 56 of the truck 40. The axle 57 in turn drives the front axle through the drive chain 65 to drive the front wheels 51 of the truck 40. It will thus be manifest that the loading machine may be driven through the traction wheels from the motor 224 either forwardly or reversely either at a high transportation speed or low feeding speed without requiring reversal of direction of rotation of the motor 224. In other words, the truck propelling mechanism may be operated at a high transportation speed by throwing in the clutch 283, 285 and at a low feeding speed by throwing in the clutch 284, 286. The truck propelling mechanism may be reversed by means of the reversing gearing shown in Fig. 4, without reversing the direction of rotation of the motor 224.

As clearly disclosed in Fig. 2, I provide a power

driven electrical cable drum 325 which is pivotally mounted on the rear bed plate 50 by a shaft journaled in a bearing 326 mounted on an arm pivoted to a bracket 327 carried on the top of an oil reservoir 328 of the hydraulic control system of the loading machine. The drum 325 is adapted to carry a flexible electrical cable which connects the source of electrical power supply to the electric motor 224. Rigidly attached to the cable drum 325 is a drive sheave 330 driven by chain 331 from a sheave 332. The ratio of the sheaves 330 and 332 is so selected that the speed of rotation of the drum 325 will be sufficient to pick up the flexible electrical cable to prevent an accumulation of slack therein even when substantially all of the cable has been paid out, with the effective diameter of the cable drum 325 at a minimum. The drum 325 must rotate at different speeds relatively to the speed of travel of the loading machine during the hauling in of the cable due to variation in the effective diameter of the drum 325. To provide for this the sheaves 330 and 332 have smooth surfaces so that the chain 331 can slip with respect thereto. If the drum 325 tends to rotate at a speed too fast for that required to take up the slack in the electric cable, there will be slippage between the chain 331 and one or both of the sheaves 330 and 332.

Furthermore, the sheave 332 is a one-way power driven sheave so that when the loading machine is operating to pay out the electric cable, the tension on the latter is relied on to rotate the drum 325, the electric cable being pulled in, of course, under power. To provide this one-way drive, the sheave 332 is journaled loosely on a cup sleeve keyed to the shaft 275. Pawl and ratchet mechanism between the cup sleeve and the sheave 332 permits rotation of the sheave 332 from the shaft 275 only when the electric cable is to be pulled in. It will therefore be seen that when the loading machine moves forward, tension on the electric cable will cause the cable drum 325 to rotate freely since the sheave 332 may be rotated freely on the shaft by reason of the slipping of the pawl and ratchet mechanism.

Secured to the sheave 332 to rotate therewith is a haulage or towing cable drum 336 (Fig. 2). A flexible steel cable is adapted to be associated with the cable drum 336, the free end of which may be connected to an anchorage in the mine extraneous to the loading machine in such position as to cause power rotation of the cable drum 336 to aid the loading machine in climbing a hill. In general, it is not necessary to use this flexible steel cable but sometimes severe conditions are encountered, making its use desirable. To effect a driving connection between the drum 336 and the countershaft 275, the former is provided with jaws adapted to co-operate with jaws of a sliding clutch member which is feathered to the end of the shaft 275 and operated by a skipper.

As shown in Fig. 2, a guide pulley 342 is carried by a bracket 343 supported by the bed plate 50 directly to the rear of the drum 336, to act as a guide for the aforementioned steel cable.

As shown at the lower left-hand corner of Fig. 2, a pair of guide pulleys 344 and 345 are provided adjacent the rear end of the frame 40 to guide the flexible steel cable from the rear of the main frame of the truck 40 to extend either forwardly or rearwardly. When the steel cable extends rearwardly it will pass directly from the pulley 342 to the pulley 344, and when the cable

is directed to the front end of the loader it will, in addition, be reeved about the pulley 345 to extend forwardly along the side of the truck 40.

It should also be noted that the rear cross-piece 46 of the main frame of the truck 40 carries a guide member 351 having top, bottom and side anti-friction rolls. The electric cable may be supported on the guide member 351 particularly when it is being paid out by forward movement 10 of the loading machine.

As was previously pointed out, the swinging of the gathering and discharge conveyors 41 and 42, about both their vertical and horizontal axes, is controlled by hydraulic motors. It is therefore necessary to provide for the control of these hydraulic motors. To this end the armature shaft of the electric motor 224 extends through the rear of the motor casing, as shown in Fig. 2, and drives a hydraulic pump 357, preferably an 15 oil pump, through a chain and sprocket drive mechanism 358. The pump 357 is preferably a relatively high pressure pump capable of producing pressure up to one thousand pounds per square inch and is mounted upon the oil reservoir 328. It will thus be seen that the pump 357 is continuously driven whenever the motor 224 is operated.

It may also be mentioned that the pump 357 is of such a construction that regardless of its direction of rotation it will always supply pressure at the same port. This is useful to maintain full control of the machine in the event that the motor 224 is driven in reverse direction.

Attention is now directed particularly to Fig. 4 illustrating the operating mechanism for controlling the reversing clutches 259 and 260 which may be operated to reverse the direction of rotation of the shaft 262 to which is keyed the pinion 272 (Fig. 4). It has been found in practice that clutches tend to become worn and I have therefore provided improved means to compensate for this wear on the clutches 259 and 260. Removably attached to the operating shaft 269 for the clutches 259 and 260 is a removable extension shaft 431 which is connected by means of the pin 432 to a rod 433 both ends of which are screw-threaded as shown in Figs. 4 and 12.

To the false bottom plate 249' is welded the upright cylindrical socket 434 for receiving the lower end of the vertical shaft bearing 435 (Fig. 13) which may be secured to the socket by means of the set screw 436. To the upper portion of reduced diameter of the shaft bearing 435 is journaled by means of the bushing 437 the arms 55 438, 438' and the spacing block 439.

Keys 440, 440' are inserted between the spacing block 439 and the arms 438, 438' as shown in Fig. 13. By means of the bolts 441, 441' the arms 438, 438' are clamped to the spacing block 60 to form a single unit. A cotter pin 442 may be relied on to retain this unit journaled on the stationary or fixed shaft bearing 435.

The spacing block 439 has extending laterally therefrom an arm 439'. The aforesaid unit thus becomes a bell-crank pivoted for rocking movements on the shaft bearing 435.

The outer end of the arm 439' extends through an opening 543 in the reciprocating plate 444, the upper and lower edges of which have tongue 70 and groove connections at 444, 445 with the upper and lower guide bars 446 and 447, as shown in Fig. 10. The upper guide bar 446 may be secured to the spacing plate 67 by means of the bolts 468, 468, as shown in Figs. 4 and 8. The lower guide bar 447 may be riveted to the spacing

plate 467 as indicated at 469 in Figs. 8 and 10. The spacing plate 467 may be secured to the plate 470 by means of bolts 471, 471, and the back plate 470 may be secured to the bottom plate 50 by means of welding as indicated at 472 in Fig. 4.

The lower end of the lever 443 is welded to the front quadrant plate 473 which is journaled by means of the bushing 474 on the bearing 475, the outer end of which is provided with a disc-shaped head 476 of enlarged diameter. Also journaled on the bearing 475 is a rear quadrant plate 477. Intermediate the quadrant plates 473 and 477 is a spacing block 478 which is also journaled by means of the bushing 474 on the bearing 475. The front and rear quadrant plates 473 and 477 are respectively pinned at 479 and 480 to the spacing block 478, as shown in Fig. 14. Lubricating means may be provided at 481. The rear end of the bearing 475 is provided with an annular shoulder 482 which fits against the front side of the spacing plate 467. The rear end of the bearing 475 is screw-threaded at 483. A nut 484 is screw-threaded on the rear end 483 to force a washer 485 against the rear side of the back plate 470 to very securely hold the bearing 475 rigidly connected to the plates 467 and 470, thereby holding the upper and lower guide bars 446 and 447 rigidly connected to the bottom plate 50 shown in Fig. 4.

By means of cotter pins 486, shafts 488, 489 are connected between the quadrant plates 473 and 477, as shown in Figs. 8 and 10. These shafts serve as journal bearings for the rollers 490, 491 which are in position to engage the cam surfaces 492, 493 of the opening in the reciprocating plate 444.

The opening 494 in the reciprocating plate 444 is horizontal at the upper portion, as indicated at 495. The lower portion of this opening is also horizontal, as indicated at 496 in Fig. 8. Either the upper horizontal portion 495 or the lower horizontal portion 496 will serve to limit the throw of the lever 443 in either direction when the rollers 490, 491 engage the same. However, it is preferred to provide centering mechanism at 497 which will also serve to limit the throw of the lever 443, and when the latter is released such centering mechanism will automatically return the lever 443 to its vertical position.

The centering mechanism comprises a bracket plate 498 bolted at 499, 499 to the reciprocating plate 444. The plate 498 is provided with a downwardly extending finger 500 through which extends a bolt 501. An angular bracket plate 502 is riveted at 503 to the guide bar 447. A spring 504 intervenes the finger 500 and the head of the bolt 501, and a spring 505 is located between the finger 500 and the bracket plate 502. By means of a nut 506 on the threaded end of the bolt 501, the finger 500 may be adjusted in accordance with the vertical position of the lever 443 and so that when the lever 443 is in its vertical or neutral position the springs will be counterbalanced. It can readily be seen that when the lever 443 is moved in an anticlockwise direction, as shown in Fig. 8, the spring 504 will be compressed, and when the lever 443 is released this spring will return the lever to neutral position. When the lever 443 is moved in a clockwise direction the spring 505 will be compressed, and when the lever is released this spring will return the lever to its neutral or vertical position.

The spacing plate 467 is provided with an opening 507 to provide ample space for the inner

ends of the shafts 488 and 489. Intermediate the ends of the opening 507 the lower portion of the plate 467 projects upwardly, as indicated at 508 in Fig. 8, to provide additional bearing for the screw-threaded end 483 of the journal bearing 475. It is this upwardly extending portion 508 which is provided with a perforation and serves as an abutment for the annular shoulder 482 shown in Fig. 14.

Between the arms 438 and 438' of the bell crank lever unit shown in Fig. 11 is located a ball bearing abutment device 509, the upper end 510 of which is journaled in the arm 438, the lower end 511 being journaled in the arm 438', as shown in Fig. 12.

The ball bearing abutment unit 509 is slideable along the rod 433, with all parts thereof remaining in the co-relation shown in Fig. 12.

Located within the cylindrical body portion 512 of the ball bearing unit 509 is a retaining ring 513 which has a peripheral flange adapted to engage a complementary flange on the body portion 512, as shown in Fig. 12. Fitted within the body portion 512 is the outer cylindrical ball bearing race 514. A cylindrical inner race 515 is slideable on the rod 433. Between the two races are located the balls 516. The retaining ring 517 is slideable on the rod 433 and has a peripheral flange which is adapted to engage a complementary flange on the ring 518. By means of rivets 519, 520, the ring 518 is secured to the body portion 512 of the ball bearing unit 509. The latter therefore has its parts in interlocking relation and is adapted to slide as a unit along the rod 433 to engage either the spring 521 or 522.

As shown in Fig. 12, abutment washers 523 and 524 are adjustable along the screw-threaded portions 525 and 526 of the rod 433 by means of the nuts 527 and 528. Additional nuts 529 and 530 are provided as lock nuts to firmly hold the nuts 527 and 528 in adjusted positions.

When by means of the lever 443 and the mechanism connected between the same and the ball bearing unit 509 the spring 521 is engaged to move the rod 431 to the left, as viewed in Fig. 4, the operating key 266 will be effective to move the operating ring 265 to the left to apply the friction clutch 259 and thereby transmit rotary movement from the motor 224 through the gearing shown in Figs. 1 and 4 to the shaft 262 in a certain direction. When the ball bearing unit 509 is moved toward the right to move the rod 431 toward the right, as viewed in Fig. 4, the clutch 260 will be applied to effect rotation of the shaft 262 in the opposite direction.

It is desirable that by means of the handle 531 the lever 443 may always be moved in one direction or the other through a certain definite angle, but the spacing between the ball bearing unit 509 and the spring 521 and the spacing between the ball bearing unit 509 and the spring 522 are variable and adjustable. In other words, a certain amount of adjustable lost motion is provided in the actuation of the rod 431 although the lever 443 is always moved through the same angle either in one direction or the other. The lost motion between the ball bearing unit and the rod 431 is initially at a maximum either for the application of the clutch 259 or the application of the clutch 260. The lost motion for each of these clutches 259 and 260 may be reduced as these clutches become worn, thereby maintaining the predetermined angle of throw of the lever 443. As the clutch 259 becomes worn the spring 522 is adjusted to a position closer to the neutral

position of the ball bearing unit 509, and as the clutch 260 becomes worn the spring 521 is adjusted to a position closer to the ball bearing unit 509. In other words, as the clutches 259 and 260 become worn, the lost motion connections 8 may be adjusted accordingly.

Movement of the lever 443 in either direction is limited by the roller 490 or the roller 491 engaging the horizontal straight surface 496 at the bottom of the opening 494 in the reciprocating plate 444. It should be noted, however, that at the ends of the horizontal surface 496 the edges curve upwardly to vertical portions 532 and 533. Consequently when the rollers 490 and 491 are moved downwardly along the vertical surfaces 532 and 533, the centers of rotation of the rollers will be below the center of rocking movement of the lever 443. In the application of either of the friction clutches 259, 260, either one or the other of the springs 521, 522 will be 10 under compression and there will be a strong back pressure on the bell crank arm 439' to exert a strong force on the reciprocating plate 444 tending to move the latter back to neutral position, but when the roller 490 or the roller 491 is moved 15 below dead center with respect to the rocking axis of the lever 443, the latter will be held in either of its lower positions and so locked there as to enable the operator to release the lever 443 with the assurance that the friction clutch 259 or 260 will be held applied. When the clutch 259 or 260 is to be released, all that the operator 20 needs to do is to release the roller 490 or the roller 491 when it is below dead center position, whereupon the centering mechanism 497 will automatically move the lever 443 to its neutral position and hold it there.

It should be particularly noted that the lever 443 need be moved only about thirty-five degrees in either direction to move one of the rollers 490 or 491 to its locking dead center position. This is decidedly advantageous in a loading machine that is used in coal mines where the available space is very limited and the operator desires to stand between a coal rib and that side of the machine where the lever 443 is located. By limiting the throw of the lever 443 to approximately thirty-five degrees in either direction, the handle 531 may be pulled or pushed approximately horizontally with the assurance that the operator can easily move the lever to its locking position or slightly beyond the dead center locking or holding position. As above explained, the throw of the actuating lever 443 in one direction or the other from its neutral position shown in Fig. 8 will always remain substantially the same, but the extent of throw of the actuating rod 431 must be varied to compensate for the wear in the clutches 259 and 260.

It should also be noted that when the lever 443 is in its upright or neutral position, as shown in Fig. 8, both of the clutches 259 and 260 will be released or disengaged and consequently the drive shaft 262 will remain stationary. The operating lever 443 may be biased to this upright or neutral position by means of the centering mechanism 497.

Attention is now directed particularly to Figs. 2 and 4 and to the means for rotating the shaft 247 to effect application of the friction clutch 229 to effect a driving of the gathering conveyor chains of the gathering conveyor 41. This means comprises a lever 448 keyed to the shaft 247 to cause rotation thereof. Through the lever 448 extends a threaded rod 449 provided with adjust-

able nuts 450 and a compression spring 451 held in place by an adjustable nut 452. The rod 449 is pivoted to an eccentric crank pin 453 the axis of which is spaced from the axis of the shaft 454 to which it is rigidly connected. The shaft 454 is journaled in a bearing box 455 carried by the plate 248. An operating handle 456 is keyed to the shaft 454.

In the positions of the parts illustrated in Figs. 4 and 5, the clutch 229 will be released. By the operator pulling the handle 456 toward him, shaft 454 will be rotated, and threaded rod 449 will be lifted by the crank action of the eccentric crank pin 453. Through the compression of spring 451, the lever 448 will rotate the shaft 247, thereby moving the collar 245 (Fig. 4) downwardly to compress the friction plates 238 through the ring 243 and the pins 242. The handle 456 is held in clutch applied position by virtue of the fact that it strikes a stop (not shown) carried by the main frame of the truck 40, slightly after the crank pin 453 passes over its dead center position. It is therefore evident that the clutch 229 will remain in clutch applied position when operating in this position, until it is disengaged by operation of the handle 456.

Suitable means (457, 464, 466, Fig. 1) may be provided on the loading machine for starting and stopping the electric motor 224 and for reversing the same. In the operation of the loading machine embodying my improvements, it may be trammed or propelled along the mine track to the place where the loading operation is to be performed. During such transportation the drive wheels of the truck will be driven at their fast speed and the electric cable will be paid out freely from the cable drum 325. The gathering conveyor will have its front end supported above the track rails. The gathering and discharge conveyors may be controlled by the operator who rides on a small platform on the truck 40 adjacent the various levers connected to valves for controlling the hydraulic motors, particularly to swing the gathering and discharge conveyors as required by the travel of the loading machine along a curved track in a mine.

Should a very steep incline be encountered it may be necessary to employ a flexible steel cable or rope associated with the drum 336 and revolve it about the two pulleys 344, 345 (Fig. 2) with the free end connected to an anchorage in the mine extraneous to the loading machine. This arrangement is particularly desirable when the traction feed tends to cause the truck wheels to slip on the mine track.

When the loading machine has reached the place where the coal is to be loaded, which coal has been previously dislodged by cutting and blasting, with part of the coal formed as loose coal and part as a semi-compact mass, the clutch 286 (Fig. 2) will be thrown in while at the same time the clutch 285 will be released, thereby operating the propelling mechanism at a slow or sumping speed. The operator will then adjust the gathering conveyor 41 and the discharge conveyor 42, the former by lowering it in contacting relation with the mine bottom in advance of the mine track, and the latter by swinging it for discharge into mine cars either on the same mine track or a parallel track.

With the conveyor mechanisms of the discharge and gathering conveyors set into operation, and with the front end of the gathering unit resting on the mine floor in advance of the mine track, the entire machine may be fed forwardly pro-

viding for a frontal attack of the gathering conveyor 41 on the coal at the bottom of the semi-compact mass of dislodged coal to be loaded. The gathering flights operate not only to gather the coal from the mine bottom but also to tear apart and loosen up the semi-compact mass which then moves forward into the mine chamber, necessitating frequent retractions of the whole machine along the mine track. With the electric motor 224 continuously operating in the same direction, the gathering conveyor may be reciprocated to more efficiently effect loading of the coal, by operating the reversing clutches 259 and 260 of Fig. 4. In other words, with the electric motor 224 continuously operating in the same direction, the operator may move the lever 443 in either direction from neutral position to effect operation of the reversing clutches 259 and 260 to effect reciprocations of the gathering conveyor during loading operations. During such reciprocations of the gathering conveyor the clutch 286 (Fig. 2) may be left in applied position so as to effect the slow movement of the truck propelling mechanism. Furthermore, whenever desired, depending upon the extent of reciprocations of the mining machine along a mine track, the electric cable on the drum 325 may be paid out or wound up in accordance with the movements of the loading machine.

A general review of the construction and operation of the loading machine shown in the accompanying drawings will demonstrate more clearly the flexibility of the adjustments to obtain the most efficient operation in loading coal by attacking a semi-compact mass of coal shot down from the face of a coal vein. By means of the vertical reciprocating hydraulic motor 194, the rear end of the discharge conveyor 169 may be adjusted in elevation. By means of the hydraulic motor 102 (Fig. 3) the front end of the gathering conveyor may be adjusted in elevation. The whole loading machine may be transported along the mine track under control of the operator who may start or stop or reverse the electric motor 224 by means of suitable controlling mechanism (457, 464, 466, Fig. 1) connected thereto. Inasmuch as the power transmission mechanism between the electric motor 224 and the gathering and discharge conveyors is in fixed relation to the latter, it is necessary for the operator to start the motor 224 in the proper direction. In order to secure upward movement of the adjacent flights along the central trough of the gathering conveyor unit, the sprockets at the upper ends of the shafts must rotate in opposite directions. This necessitates the movement of the gear 254 clockwise and the movement of the gear 251 anti-clockwise. Therefore the gear 240 (Fig. 1) must move clockwise as viewed in plan, and to secure such rotation the armature shaft 225 must rotate clockwise when viewed from the right-hand end thereof in Fig. 1.

Since the gears 227, 240 and 236 rotate together with the shaft 230 when the clutch 229 is applied, the gear 236 will be rotated clockwise as viewed in plan in Fig. 1. As shown in Fig. 2, the sprocket 297 is located on the left-hand side of the loading machine looking forward, and consequently when the gear 236 rotates clockwise, as viewed in plan, the gear 258 will effect clockwise rotation of the shaft 262, as viewed in Fig. 1. This is the proper rotation for causing the sprocket chain 302 to rotate the sprocket 189 in a clockwise direction, as viewed in Fig. 1, to drive the conveyor chain 165 of the discharge conveyor 42

in the proper direction for discharging the coal into mine cars. During normal operation of the gathering conveyor and discharge conveyor the operator has no occasion for reversing the motor 224, but if the gathering flights become stalled in the semi-compact mass of coal adjacent the coal vein, it sometimes is desirable to reverse the electric motor 224 in order to loosen the conveyor flights from the coal mass. Such reversal of the electric motor 224, however, does not interfere with the operator's manipulation of the reversing clutches 259, 260 of Fig. 4 to effect rearward movement of the loading machine along a mine track in order to assist in releasing the coal flights from the coal mass. During loading operations, the electric motor 224 should always be operated in such direction as to effect proper direction of travel of the gathering conveyor and the discharge conveyor, the reversing clutches 259 and 260 of Fig. 4 being then relied upon to effect reversal of travel of the whole loading machine along the mine track.

The truck propelling mechanism comprises power transmission mechanism between the electric motor 224 and all of the wheels of the truck. This power transmission mechanism is primarily under the control of the main friction clutch 229 shown in Figs. 1 and 4. The operator may apply or release the clutch 229 by means of the lever 456 as shown in Fig. 5. The truck propelling power transmission mechanism also includes the reversing clutches 259 and 260 shown in Fig. 4, either of which may be applied by the operator actuating the lever 443 in one direction or the other, as shown in Figs. 2 and 3, and consequently the loading machine during operation may be moved along the mine track in either direction without reversing the electric motor 224 but even if the electric motor 224 is reversed for the purpose above explained, the loading machine may be moved in either direction along the mine track at any time by means of the reversing clutches 259 and 260 of Fig. 4.

When the shaft 262 of Fig. 4 is rotated in one direction or the other, the pinion 272 thereon drives the reduction gearing shown in Fig. 2, which is under the control of the clutches 286 and 285 for the purpose of securing relatively low speed and relatively high speed of transmission to the shaft 275. The clutches 285 and 286 are controlled by means of the mechanism shown in Figs. 4 and 5, including the operating lever 290. A sprocket chain drive comprising the sprocket 293 on the shaft 275 connects the latter with the axle 51, as shown in Fig. 2. It will thus be seen that the electric motor 224 may be continuously operated in the same direction, while by means of the clutches 259 and 260 of Fig. 4 the gathering mechanism may be moved forwardly or rearwardly under the control of the operator, and such forward or rearward movement may be at relatively fast speed or relatively slow speed under the control of the clutches 285 and 286 of Fig. 2. A slow, powerful sumping movement into the semi-compact mass of shot down coal may thus be effected, and whenever desired a slow, powerful withdrawal movement of the gathering mechanism may be effected.

The starting and stopping of the pair of endless chains 91 of the gathering conveyor are controlled by the main clutch 229 shown in Figs. 1 and 4. During normal operation of the gathering conveyor the flights thereof move in pairs toward the discharge conveyor unit 42 and therefore the motor 224 should be continuously oper-

ated in the same direction. If there is an over-load on the gathering conveyor chains due to contact between the flights thereof and the solid or irremovable coal caught between the conveyor and roof of the mine chamber, the friction clutch 229 will slip, whereupon the proper clutch 259 or 260 may be operated to cause the machine to move rearwardly to effect release of the caught coal.

The chain 165 of the discharge conveyor unit 42 is connected by means of the sprocket chain gearing to the shaft clutch housing 295 (Fig. 4) and bevel gear 258. The direction of rotation of the gear 258 and sprocket 297 (Fig. 4) is controlled by the main motor 224 to secure proper direction of rotation of the shaft 198 to move the discharge conveyor along the conveyor trough 171 to convey material rearwardly into the mine car. It should be particularly noted by reference to Fig. 4 that notwithstanding the association of the clutch 259 with the bevel gear 258 and the shaft 262, the sprocket 297 may always be rotated in the same direction when the motor 224 is rotated in a given direction.

The cable reel 325 may be operated by power to wind up the electric cable thereon, this cable containing the insulated wires connecting the motor 224 to the distant source of electric power supply. The pawl and ratchet mechanism above referred to, permits the paying out of the electric cable as the loading machine moves forward along the mine track.

When the shaft 275 (Fig. 2) is rotated in a clockwise direction as viewed from the right-hand side of the machine the truck wheels are also being rotated to obtain, if possible, traction feed. The rope drum 336 and the truck propelling mechanism, therefore co-operate to secure very powerful forward feed of the machine particularly when the nose of the gathering conveyor unit is to be forced into a semi-compact mass of shot down coal to be loaded.

When the shaft 275 is rotated in an anti-clockwise direction as viewed from the right-hand side of the machine, the truck wheels will be rotated to retract the machine along the mine track, the steel cable on the rope drum 336 will be paid out and the pawl and ratchet mechanism will drive the rope drum 325 to wind up the electric cable thereon.

When the shot down coal at the coal face is to be loaded considerable power may be necessary to ram the nose of the gathering conveyor along the mine bottom into the "tight" coal, and for this purpose the traction of the wheels 51, 56 may be insufficient and under such conditions the use of the rope drum 336 and a wire cable anchored extraneously to the machine may be advisable. However, it should be understood that in order to protect the truck propelling mechanism the clutches 259 and 260 may each be set to slip when the load on the clutch reaches a predetermined limit.

The clutches are individually operable and the actuating mechanism for each may be individually adjusted. Each clutch is yieldingly applied and each may be set to slip upon reaching a predetermined load. Therefore, by reason of the springs 521 and 522 the regulation of slipping at certain loads may be sufficiently sensitive to more efficiently protect the propelling mechanism.

It will thus be seen that the adjustment of the lost motion connections between the ball bearing unit 509 and the springs 521, 522 is not only for

the purpose of taking up wear in the friction clutches from time to time but also for the purpose of regulating the point of slippage of each clutch in accordance with the load on the clutch. Under normal conditions slippage of the clutches may occur when the loads thereon are relatively small so as to maintain a high factor of safety. When the shot down coal remains standing in a semi-compact mass, the slippage may be set for a relatively large load, particularly when the gathering mechanism is moved forward into such semi-compact mass, although under such circumstances the factor of safety may be lowered. By reason of the springs 521, 522 the adjustments of the points of slippage may be varied over a wide range. Of course, when either clutch slips the operation of the propelling mechanism is discontinued and movement of the loading machine along the mine track stops.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a machine of the class described, the combination with a driven shaft, of reversing friction clutches associated therewith, mechanism comprising a rod movable axially of said shaft for applying said friction clutches, an operating lever, mechanism comprising dead-center means for limiting each movement of said lever to its opposite positions from neutral to substantially less than 90° and locking said operating lever at its limiting positions, and connections comprising adjustable abutment mechanism on said rod for varying the extent of movement of the latter axially of said shaft in applying either of said friction clutches.

2. In a machine of the class described, the combination with a clutch, of a pivoted operating lever, a cam device, mechanism for guiding said cam device to reciprocate rectilinearly, means on said lever in position to engage said cam device to move the same rectilinearly when said lever is moved on its pivot, mechanism limiting the movement of said engaging means to a position just beyond dead center relative to the pivot of the lever to effect locking of the latter just beyond such dead center position, and clutch actuating mechanism between said cam device and said clutch.

3. In a machine of the class described, the combination with a clutch, of a pivoted operating lever, a movable cam plate, mechanism for guiding said plate for movement along straight lines, means on said lever for engaging said cam plate to move the same rectilinearly in opposite directions, mechanism limiting the movement of said engaging means to opposite positions beyond dead centers relative to the pivot of the lever to effect locking of the latter adjacent such dead center positions, and clutch actuating mechanism between said cam plate and said clutch.

4. In a machine of the class described, the combination with a clutch, of a pivoted operating lever, a cam plate, mechanism for guiding said cam plate for rectilinear movements in opposite directions, means on said lever for engaging said cam plate, actuating connections between said cam plate and said clutch, means for effecting

locking of the lever in clutch applied position, and resilient means for automatically returning said lever to initial position when released from said locking means.

5. In a machine of the class described, the combination with a driving shaft, of a driven shaft, reversing mechanism comprising spaced friction clutches between said shafts, an operating lever pivoted for predetermined movements in opposite directions from neutral position, a cam device, means on said lever in position to engage said cam device to move the same predetermined distances in opposite directions relative to the neutral position of said operating lever, means affording approximate dead center locking positions for said operating lever at its opposite limits of movement, and actuating connections between said cam device and said driven shaft, said connections including a rod movable axially of said driven shaft in opposite directions to effect application of either of said friction clutches and said connections also including adjustable abutment mechanism on said rod for varying the extent of movement of said axial actuating device to compensate for wear in the clutches.

6. In a machine of the class described, the combination with reversing clutches, of a cam plate having a relatively large opening therein affording spaced opposite cam surfaces, a pivoted actuating lever, spaced-apart actuating devices carried by said lever for respectively engaging said opposing cam surfaces and serving to move said cam plate in opposite directions when said lever is moved in opposite directions, and connections between said cam plate and said clutches for applying the latter when said lever is actuated.

7. In a machine of the class described, the combination with spaced clutches, of an actuating lever, a cam plate having an opening therein relatively wide at one portion and narrower at another portion to afford opposing cam surfaces, spaced-apart cam engaging devices on said lever at the relative wide portion of said opening when the lever is in neutral position, mechanism for guiding the cam plate in opposite directions when shifted by movement of said cam engaging devices in opposite directions to the narrower position of said opening, and connections between said plate and said clutches to effect operation of the latter when said plate is shifted.

8. In a machine of the class described, the combination with spaced friction clutches, of an actuating rod movable axially of said friction clutches to apply the same, spaced abutment nuts threaded on said rod, buffer springs associated with said abutment nuts, a bell-crank one arm of which is in position to engage either of said buffer springs to move said rod axially, a cam plate having an opening to receive the other arm of said bell-crank, an actuating lever, rollers carried by said lever in position to engage opposing cam faces in said plate, and means for limiting the throw of said actuating lever in opposite directions to locking positions just beyond dead centers so that when said actuating lever is released the applied clutch will not be released.

9. In a machine of the class described, the combination with a driving shaft, of a driven shaft, a clutch adapted to connect said shafts, a pivoted operating lever, a movable cam device, mechanism guiding said cam device for movement rectilinearly, means on said lever in position to engage said cam device to move the same rectilinearly when said lever is moved on its pivot, mechanism limiting the movement of said engag-

ing means to a position just beyond dead center relative to the pivot of the lever to effect locking of the latter just beyond such dead center position, and clutch actuating mechanism between said cam device and said clutch.

10. In a machine of the class described, the combination with a friction clutch, of means comprising an axially movable rod for applying said clutch, an abutment mounted on said rod for adjustment therealong, and mechanism comprising an actuating device spaced from said abutment but movable along said rod into engagement with said abutment to effect axial movement of said rod and the application of said clutch, the construction and arrangement being such that such actuating device has a predetermined lost motion from neutral before engaging said abutment to apply said clutch.

11. In a machine of the class described, the combination with a friction clutch, of mechanism comprising a pivoted lever for applying said clutch, an actuating plate, mechanism for guiding said plate for reciprocating movements in a plane extending transversely of the plane in which said lever is movable, an actuating lever, mechanism supporting said actuating lever for pivotal movement in a plane parallel to said plate and transversely of the plane of said first-named lever, and adjustable clutch pressure mechanism for transmitting movement from said first-named lever to apply said clutch variably.

12. In a machine of the class described, the combination with a drive shaft, of a driven shaft, reversing mechanism between said shafts comprising two friction clutches, means comprising an axially movable rod for applying said clutches, spaced-apart abutments mounted on said rod each for adjustment therealong, and mechanism comprising an actuating device between said abutments and movable along said rod into engagement with either of said abutments to apply one of said clutches, the construction and arrangement being such that such actuating device when in neutral position is spaced from both of said abutment devices and has predetermined lost motions from neutral before engaging said abutments to apply said clutches.

13. In a machine of the class described, the combination with a friction clutch, of means comprising a rod movable axially to apply the clutch, an abutment mounted on said rod, an actuating unit mounted on said rod to slide along the same toward and from said abutment, and means for sliding said actuating unit along said rod to engage said abutment to effect axial movement of said rod and the application of said clutch.

14. In a machine of the class described, the combination with a driving shaft, of a driven shaft, means comprising two friction clutches for connecting said shafts for operation of the driven shaft in reverse directions, an operating lever, an actuating rod connected to said friction clutches, an actuating abutment connected to said lever and slidable along said rod, resilient abutments on said rod on opposite sides of said actuating abutment, and means for operating said lever to slide said actuating abutment along said rod against either of said resilient abutments and thereby secure axial movement of said rod and the application of one of said clutches.

15. In a machine of the class described, the combination with a friction clutch, of a cam device comprising a cam plate having an actuating 75 cam surface merging into a locking cam surface,

an actuating lever, operating mechanism between said cam plate and said clutch, means located on said actuating lever in position to engage said cam surfaces one after the other, and mechanism for pivotally mounting said actuating lever in position to enable said engaging means to move along said cam surfaces to first apply the clutch and then lock it in applied position, the construction and arrangement being such that when the locking cam surface is engaged as aforesaid the 10 said engaging means is at or beyond dead center relative to the pivot of said actuating lever.

16. In a machine of the class described, the combination with a friction clutch, of an operating lever, a cam device comprising an actuating 15 cam face merging into a locking cam face, mechanism for guiding the actuating movement of said cam device, operating connections between said cam device and said mechanism on said operating lever in position to engage said cam faces one 20 after the other when the lever is moved through an angle of about thirty degrees, and means for pivotally mounting said operating lever in position to enable said locking surface to establish a dead center holding position for said lever.

17. In a machine of the class described, the combination with a clutch, of a cam plate having an actuating cam surface and a locking cam surface, an actuating lever, mechanism for supporting said cam plate for actuating movement, operating connections between said cam plate and said clutch, means on said lever for engaging said cam surfaces one after the other to effect application of the clutch and the locking thereof in applied position, mechanism pivotally mounting said lever in position to effect dead center locking of said lever when said engaging means is associated with said locking cam surface, and means at one end of said locking cam surface for limiting the throw of said lever to approximately thirty 40 degrees from neutral position, the construction and arrangement being such that notwithstanding such limited throw of said lever the said engaging means is associated with said locking cam surface to provide a dead center connection relative to the pivot of said lever to hold the latter in its clutch applying position after being manually released.

18. In a machine of the class described, the combination with clutch mechanism, of an actuating lever, a cam plate having an actuating cam surface merging into a locking cam surface, a cam engaging device on said lever, mechanism pivotally mounting said lever in position to enable said cam engaging device to co-act with said locking cam surface to hold such device at dead center relative to the pivot of said lever, mechanism for guiding said cam plate in opposite directions in accordance with the position of said cam engaging device, and operating connections between said plate and said clutch mechanism.

19. In a machine of the class described, the combination with a friction clutch, of mechanism comprising a rod connected to said clutch to apply the same, an abutment adjustable to various positions along said rod, a manual operating lever, an actuating device spaced from said abutment but movable into engagement therewith, and means between said lever and said actuating device to operate the latter to effect application of the clutch, the extent of movement of the actuating device before engaging said abutment being dependent upon the extent of movement necessary in securing application of the clutch.

20. In a machine of the class described, the

combination with spaced friction clutches, of an actuating rod movable axially of said friction clutches to apply the same, spaced abutments on said rod each adjustable along said rod to various positions thereon, an actuating device between said abutments and spaced from both of them, an operating lever, mechanism limiting the throw of said lever through a predetermined angle, and mechanism between said lever and said actuating device to slide the latter along said rod into engagement with said abutments, the construction and arrangement being such that when said lever is moved through a predetermined angle one of said abutments will be moved to such extent as will take up wear in the clutch and apply the latter with a force predetermined by the adjustment of the corresponding abutment along said rod.

21. In a machine of the class described, the combination with a friction clutch, of means comprising a rotary rod movable axially to apply the clutch, an abutment mounted on said rod and adapted to rotate therewith, an actuating unit mounted to rotate on said rod and to slide along the same toward and from said abutment, and means for sliding said actuating unit axially along said rod to engage said abutment to effect axial movement of said rod and the application of said clutch.

22. In a machine of the class described, the combination with a friction clutch, of means comprising a rotary rod movable axially to apply the clutch, an abutment mounted on said rod, a ball-bearing actuating unit mounted to rotate on said rod and to slide along the same toward and from said abutment, and means for sliding said ball-bearing actuating unit along said rod to engage said abutment to effect axial movement of said rod and the application of said clutch, the construction and arrangement being such that when the clutch is applied the sliding means is stationary while said rod and said ball-bearing unit rotate relatively to said sliding means.

23. In a machine of the class described, the combination with a friction clutch, of means comprising a rod movable axially to apply the clutch, an adjustable resilient abutment on said rod, an actuating unit mounted on said rod to slide along the same toward and from said resilient abutment, said actuating unit when in neutral position being spaced from said resilient abutment, and means for sliding said actuating unit along said rod to engage said abutment to effect axial movement of said rod and the application of said clutch.

24. In a machine of the class described, the combination with a clutch, of a cam device having an actuating cam surface and a locking cam surface, an actuating device, mechanism for supporting said cam device for actuating movement, operating connections between said cam device and said clutch, said operating connections being separate from said cam surfaces, means on said actuating device for engaging said cam surfaces one after the other to effect application of the clutch and the locking thereof in applied position, mechanism mounting said actuating device in position to effect such locking, and means at one end of the locking cam surface for limiting the throw of the actuating device from neutral position, the construction and arrangement being such that when said actuating device is at the limit of its throw from neutral said locking of the application of the clutch will continue even after said actuating device is released.

25. In a machine of the class described, the combination with a driving shaft, of a driven shaft, reversing mechanism comprising spaced friction clutches between said shafts, an operating lever pivoted for movements of substantially less than 60° in either direction from neutral position to either one of two dead center positions, means for applying either clutch comprising an additional lever, adjustable lost-motion take-up mechanism between said additional lever and said friction clutches, a plate having two openings therein one for receiving one arm of said additional lever, the other opening having spaced-apart cam faces, and transmitting connections between said operating lever and said plate at said cam faced opening comprising dead-centering mechanism, the construction and arrangement being such that the throw of the operating lever from neutral position in either direction always remains the same to maintain the dead-centering positions of the operating lever but the extent of application of the clutches may vary individually according to the adjustment of said lost-motion take-up mechanism.

26. In a machine of the class described, the combination with a driving shaft, of a driven shaft, power transmission mechanism between said shafts comprising a clutch, a pivoted operating lever, a movable cam device having a cam opening therein, mechanism for guiding said cam device rectilinearly, means extending from said operating lever into said cam opening for effecting movement of said cam device rectilinearly and the locking thereof slightly beyond a dead-center position relative to the pivot of the lever, and clutch actuating mechanism between said cam device and said clutch.

27. In a machine of the class described, the combination with a shaft, of means comprising friction clutches for effecting reversal of rotation of said shaft, an operating lever, a cam device having a cam-faced opening therein, means connected to said lever and extending into said cam-faced opening in position to co-act with the ends of opposed cam faces of said opening to limit the throw of said lever in either direction from neutral position, and lost-motion operating connections between said cam device and said clutches, said last-named connections being adjustable to effect a variation in the application of the clutches in accordance with the wear thereof and thereby secure regulation of the slipping of said clutches when a predetermined load thereon is reached.

28. In a machine of the class described, the combination with reversing means comprising two separate friction clutches, of a manual operating lever, a cam plate, means between said lever and a cam-faced opening in said plate for limiting the throw of said lever in either direction from neutral and locking the same in either position spaced from neutral, and actuating mechanism between said cam plate and said friction clutches for applying the latter, said actuating mechanism being adjustable for each of said clutches to vary the pressure applied to each clutch independently of the other, the construction and arrangement being such that for a predetermined movement of the operating lever in either direction from neutral the throw of each clutch will be in accordance with the wear thereof to secure the desired applied pressure on each clutch independently of the other.

29. In a machine of the class described, the combination with a driving shaft, of a driven shaft, means comprising a friction clutch for connecting said shafts, a cam device comprising an actuating cam surface merging into a locking cam surface, an actuating lever, operating mechanism between said cam device and said clutch, means on said actuating lever to engage said cam surfaces, and mechanism for pivotally mounting said actuating lever in position to enable said engaging means to move along said cam surfaces successively to first apply the clutch and then lock it in applied position at or beyond dead center relative to the pivot of said actuating lever.

30. In a machine of the class described, the combination with a driving shaft, of a driven shaft, reversing mechanism comprising friction clutches associated with said driven shaft, mechanism comprising a rod in alignment with and movable along the center of the driven shaft axially thereof for applying said friction clutches, an operating lever, mechanism comprising dead-center means for limiting the movement of said operating lever to its opposite positions from neutral and locking said lever in its limiting positions, and connections between said lever and said rod comprising adjustable abutment mechanism spaced apart on said rod for varying the extent of movement of said rod axially of said driven shaft in applying either of said friction clutches for controlling the reversal of rotation of said driven shaft.

EDWARD G. LEWIS.
